GOLF CLUB HEAD

Jay Frank Ray, 1641 R St. NW., Washington, D.C.

Filed Sept. 25, 1961, Ser. No. 66,844

Term of patent 14 years

(Cl. D34—5)

Fig. 1.

Fig. 2.

Fig. 3.

Fig. 5.

FIG. 1 is a perspective view of the golf club head showing my new design;

FIG. 2 is a top plan view thereof;

FIG. 3 is a front elevation thereof;

FIG. 4 is a right end view of FIG. 3;

FIG. 5 is a left end view of FIG. 3; and

FIG. 6 is a bottom plan view of FIG. 3.

The fragmentary broken line showing of a shaft in the drawing is for illustrative purposes only.

I claim:

The ornamental design for a golf club head, as shown and described.
